LASTING MACHINE

Lloyd G. Miller, Beverly, Mass., assignor to United
Shoe Machinery Corporation, Flemington, N. J.,
a corporation of New Jersey.

Application September 18, 1946; Serial No. 697,784.

27 Claims. (Cl. 12—8.3)

1.

This invention relates to lasting machines, and has for an object the provision of a new and improved lasting machine which is efficient and speedy in operation, easy to operate and of simple construction. The invention is herein illustrated as embodied in a machine for lasting with an adhesive in which the stock to be lasted is tensioned by drawing its lasting margin inwardly from the edge of, and over, the bottom of a shoe, in different locations successively along the edge of the shoe bottom, and is thereafter secured in lasted position by pressing its lasting margin against the bottom of the shoe in each location to cause it to adhere thereto. It is to be understood, however, that features of the invention are not limited to use in a machine for lasting with adhesive but are of broader utility and adapted for use in other types of lasting machines.

With the aforementioned object in view, the herein illustrated machine is, in accordance with a feature of the invention, provided with novel tensioning means comprising a rotary member having a plurality of circumferentially spaced abutments together with means cooperating with each of said abutments, in succession, for seizing successive narrow portions of the lasting margin of the stock and drawing each portion inwardly from the edge of, and over, the bottom of a shoe, thereby to tension the stock at different locations along the edge of the shoe bottom as the shoe is moved relatively to the tensioning means, and wiping means for pressing the lasting margin of the tensioned stock against the bottom of the shoe in each location. More particularly, the rotary member is a disk formed with axially extending abutments and rotated at a relatively high speed. The means cooperating with the disk preferably, and as herein illustrated, comprises a finger which is pivotally mounted adjacent to the disk and means are provided for moving the finger toward and away from the disk in such a way that an operating face on the finger cooperates with each abutment on the disk in succession, first to seize a narrow portion of the lasting margin of the stock and to tension it as the disk rotates, then to release the stock. As the stock is seized between the operating face of the finger and an abutment on the disk, the finger is arranged to yield, as the disk rotates and before the finger is moved to release the stock, so that a yielding grip is provided. Immediately after the stock has been tensioned, its lasting margin is pressed firmly against the bottom of the shoe by wiping means, preferably, and as

2.

herein illustrated, a rotary wiper having an operating face formed of a plurality of circumferentially spaced helical ribs.

For positioning the shoe with respect to the tensioning and wiping instrumentalities just mentioned, the herein illustrated machine is provided with a shoe-bottom rest and an edge gage roll. Preferably, and in accordance with a further feature of the invention, the shoe-bottom rest is so arranged that the stock as it is tensioned by the rotary tensioning means is drawn over a portion of the shoe-bottom rest, thereby to prevent distortion of the edge of the shoe-bottom part, such, for example, as an insole or the platform of a "slip-lasting" shoe, and also to relieve the operator of the effort that otherwise would be required to hold the shoe in place against the pull of the tensioning means. The edge gage roll is arranged to engage the side of the shoe frictionally, and in order to facilitate movement of the shoe relatively to the tensioning and wiping instrumentalities at a uniform rate, the roll is, in accordance with a still further feature of the invention, power driven at a speed suitably related to the speed of the rotary disk and the movement of abutments thereon. Preferably the arrangement is such that substantially every portion of the lasting margin of the stock is subjected to the action of the tensioning and wiping instrumentalities as the lasting operation proceeds along the edge of the bottom of the shoe.

After the lasting operation has been performed, it is a usual practice, where the outer sole is to be attached by adhesive, to apply a band of adhesive to the exposed surface of the lasting margin of the stock. This operation, which is performed either by hand or by means of a separate machine, takes some time and after this band of adhesive has been applied, it must be permitted to dry to a so-called tacky state before the outer sole can be attached. To avoid the extra labor and delay involved in this operation, the herein illustrated machine is, in accordance with another feature of the invention, provided with means, adjacent to the wiping means, for spreading a band of adhesive on the exposed surface of the lasting margin of the stock during the lasting operation. Thus, after the shoe has been lasted and the adhesive dried, the outsole may be attached without any extra operation being performed.

The above and other objects and features of the invention will appear in the following detailed description of the preferred embodiment

thereof illustrated in the accompanying drawings and will be pointed out in the claims:

In the drawings,

Fig. 1 is a view in front elevation of a machine embodying the features of this invention;

Fig. 2 is a plan view of the machine shown in Fig. 1;

Fig. 3 is a view in side elevation and with certain parts in section of the machine shown in Fig. 1;

Fig. 4 is a view in side elevation of certain of the operating elements of the machine; and

Fig. 5 is a plan view on an enlarged scale of operating mechanism forming part of the machine.

Referring now to the drawings, the operating elements of the machine therein illustrated comprise a rotary disk 10, a finger 12, a rotary wiper 14 and a cement-applying nozzle 16, with respect to which the shoe is positioned and guided, during the operation of the machine, by means of a shoe-bottom rest 18 and an edge gage roll 20. These elements are supported on, and operated by mechanism contained in, a frame construction including a base plate 22, three vertically extending uprights 24, 26 and 28 and an upper cross member 30. A main drive shaft 32, journaled in bearings 34 and 36 mounted, respectively, in the cross member 30 and a web 38 which extends laterally from the upright 28, is provided with a pulley 40 for receiving power from a suitable source (not shown).

The disk 10 is formed integrally with a gear 42 and a shaft 44 which is journaled, at one end, in a thrust bearing 46 mounted on the upright 28, Figs. 1 and 2. Between this bearing and the gear 42, the shaft 44 is rotatably mounted in a bushing 47 supported by a sleeve 48. This sleeve is journaled in a bearing bore 49 formed in an ear 50 that extends downwardly from a web 52 that extends laterally from the upright 28, Figs. 1 and 5. The gear 42 meshes with an idler gear 60 which is journaled on a stud 61 and driven by a gear 62 carried by a cross shaft 64, Fig. 1. This cross shaft is journaled in bearings 66 and 68, mounted on the upper portions of the uprights 24 and 26, and is driven from the main drive shaft 32 by means of bevel gears 70 and 72, Fig. 2. The disk 10 has on one of its faces a circumferential series of axially extending abutments 80, 80, formed to present angularly disposed operating faces 82, 82, see Figs. 3 and 4, there being six of these abutments in all in the herein illustrated machine.

The finger 12 is offset at 84 in order to pass around the gear 42, see Fig. 5, and has a serrated operating face 86 for cooperating with the operating faces 82 of the abutments 80, in succession, as will be presently explained. This finger is press-fitted onto one end of the bushing 47 and has a rearwardly extending arm portion 88. A clamp nut 90 is threaded onto the opposite end of the bushing 47 and serves to draw the finger 12 against the sleeve 48 and thus hold finger 12, bushing 47 and sleeve 48 together as a unit which is rotatably and slidably mounted in the bore 49 of ear 50. This sleeve is provided with spaced flanges 92, 94, between which are positioned the ends of a yoke 96 formed on one end of a lever 98. This lever is pivotally mounted on a stud 100, carried by the web 52, Figs. 2 and 3, and on its opposite end has two arms 102 and 104 which embrace an eccentric 103 carried by the main drive shaft 32, Fig. 5. The arm 102 is formed integrally with the lever 98 while the other arm

104 is pivoted thereto on a pin 106 and is yieldingly urged against the eccentric 103 by means of a compression spring 108 one end of which engages a plug 110 threaded into the arm 104. A nut 112 is provided for locking the plug after the compression of spring 108 has been adjusted by rotating the plug which has a slot 114 adapted to receive a tool for the latter purpose. The eccentric as it rotates, oscillates the lever 98 thereby to reciprocate the sleeve 48, together with the bushing 47 and finger 12, axially of the shaft 44 so that the operating face 86 of the finger is first positioned in alignment with an operating face 82 of an abutment 80 on the disk 10, see full-line position of the parts in Fig. 5, and then moved, in an axial direction, away from the disk to the dotted-line position shown in Fig. 5 in which the operating face 86 is out of alignment with the abutments 80.

20 The finger 12 is constantly urged to swing about the axis of the shaft 44 in a counterclockwise direction, as viewed in Figs. 3 and 4, by means of a tension spring 120 which is stretched between an eye 122 on the arm portion 88 of the finger and an adjusting screw 124 which is threaded into a bracket 126 mounted on the top surface of the web 52. Such swinging movement of the finger in this direction, when its operating face 86 is out of alignment with an abutment 80 on the disk 10, see dotted-line position of Fig. 5, is limited by means of a stop pin 128 which projects from the ear 50. This pin is so located as to hold the finger 12 in the position shown in Fig. 3 as the sleeve 48 is shifted to the left, Fig. 5, again to bring the operating face 86 of the finger into alignment with the operating face 82 of the next succeeding abutment 80 on the disk 10. The arrangement is such that the arm portion 88 is moved beyond the pin 128 just as the next abutment 80 reaches a position a little beyond that shown in Fig. 3, and substantially at the edge of a shoe held against the edge gage roll 20, whereupon the finger is released to the action of the spring 120 which moves it in a direction to clamp the lasting margin of the stock to be lasted, herein illustrated as an upper U assembled, with an insole I on a last L, against the abutment 80. As the finger 12 completes its movement to the left, Fig. 5, a portion of the lasting margin will be interposed between the finger 12 and the side face of the disk 10 between the abutments. The yielding arrangement of the arm 104 accommodates the material in this location.

55 The bottom rest 18, which is secured to the outer end of the web 52 by bolts 130, Fig. 3, has a flat end portion 132 which extends in a direction lengthwise of a shoe as it is presented to the machine and is arranged to bear on the edge of the shoe bottom, e. g., the insole I, in the zone of operation of the disk 10 and finger 12, see Fig. 1. The shoe-bottom rest is also provided with a vertically extending rib 134 which serves as a deflector to direct the lasting margin of stock to be lasted into a position to be engaged by the abutments 80 and finger 12.

60 Referring again to Figs. 3, 4 and 5, the operation of the abutments 80, on the disk 10, and the cooperating finger 12 to seize a narrow portion of the lasting margin of the upper U and 65 to draw the lasting margin inwardly from the edge of, and over, the bottom of a shoe, thereby to tension the upper at different locations along the edge of the shoe bottom as the shoe is moved relatively to the disk and finger, will now be explained. In Fig. 3 and also in Fig. 5, dotted-

time position of the parts, the finger 12 has been shifted away from the disk 10, i. e., lengthwise of the shoe and to the right in Fig. 5, so that its operating face 86 is out of alignment with the abutment 80 and has been swung in a counterclockwise direction about the axis of shaft 32 by the spring 120, until the arm portion 88 is in engagement with the stop pin 128. When a shoe is presented to the machine with its side in engagement with the edge gage roll 20 and the edge of the shoe held up against the flat end portion 132 of the bottom test 12, the lasting margin of the upper will come between the operating face 86 of the finger 12 and the operating face 82 of the adjacent abutment 80. Now, as the disk 10 rotates and the finger 12 is shifted lengthwise of the shoe and to the left, Fig. 5, by the eccentric 103, just as the operating face 82 of the abutment 80 reaches the edge of the shoe bottom, the arm portion 88 passes beyond the stop pin 128 and the finger 12 is swung in a counterclockwise direction and toward the face 82 of the approaching abutment 80. The lasting margin is thus seized, yieldingly because of the action of spring 120, between the finger 12 and an abutment 80, which act as gripper jaws, and as the disk continues to rotate, is drawn inwardly from the edge of the shoe bottom and tensioned above the last. As the stock is thus drawn inwardly, it passes over the front edge of the flat portion 132 of the bottom test so that the pull applied to the upper has no tendency to move the shoe outwardly and away from the edge gage roll 20, i. e., to the left in Fig. 4, nor is the force of the pull applied directly to the edge of the insole 1, which might be displaced or distorted thereby. During this tensioning action, the finger 12 begins to move to the right and away from the disk 10, Fig. 5, but so long as the operating face 86 is in front of the operating face 82, the grip on the lasting margin is maintained and the pull on the upper continued. However, when the finger 12 has moved far enough in this direction to bring its operating face 86 out of alignment with the operating face 82 on the abutment 80, the grip is released. At this instant, the arm 88 is moved against the stop pin 128 which limits movement of the finger as it is thus swung in a counterclockwise direction by the spring 120. Immediately thereafter, the eccentric 103 shifts the finger again to the left, Fig. 6, so that the operating face 86 of the finger 12 is moved into alignment with the face 82 of the next succeeding abutment 80 and the tensioning operation is repeated on a narrow portion of the lasting margin adjacent to that previously acted upon. Thus as the shoe is moved relatively to the disk 10 and finger 12, each succeeding narrow portion of the lasting margin of the upper, in different locations along the edge of the shoe bottom, is subjected to a pull directed inwardly from the edge of the shoe bottom and is tensioned over the last.

The rotary wiper 14 comprises a disk formed integrally with a shaft 140 which is rotatably mounted in bearings 142, 144 carried by a housing 145 mounted on forwardly projecting portions 146, 148 of the uprights 24 and 26, see Figs. 1 and 2. This shaft is driven from the cross shaft 64 by means of a belt 150 which runs over pulleys 152 and 154 carried by the cross shaft and shaft 140, respectively. Preferably, and as herein illustrated, this disk is provided with a peripheral operating face comprised of a circumferential series of axially offset helical ribs 156 and 158 similar in construction to the rotary wiper dis-

closed and claimed in United States Letters Patent No. 2,356,894, granted December 7, 1948, on an application filed in the name of Lloyd G. Miller. These helical ribs are so arranged as to provide a wiping action having a component of motion in the direction of feed of the shoe and also to impart a rapid series of hammer-like blows to the lasting margin of the upper which greatly facilitate adherence thereof to the shoe bottom part, e. g., the insole 1.

The rotary wiper 14 is positioned close to the disk 10 so that as each narrow portion of the stock, in different locations along the edge of the shoe bottom, is tensioned and drawn inwardly over the bottom of the shoe, by the action of the abutment 80 on the disk 10 and the finger 12, as above explained, it is immediately wiped in and pressed firmly against the shoe bottom by the wiper in each of these locations.

The cement applying nozzle 16 is positioned immediately adjacent to the wiper and comprises a fitting 160 secured to the housing 145 by means of screws 162, 164, and a downwardly extending neck 164, Fig. 1. A conduit 166 connects with bores 168, 170, in the fitting 160 and neck 164, respectively, and this conduit is adapted to be connected to a pump or other suitable device, not shown, for delivering adhesive under pressure. The bore 170 opens through the lower end of the neck 164 which bears on the overstated portion of the upper. Thus as the lasting operation proceeds, a band of adhesive is applied to the exposed portion of the lasting margin of the upper.

For moving the shoe relatively to the tensioning, wiping and adhesive-applying means described above, at a uniform speed, the edge gage roll 20 is utilized. This roll, which is preferably constructed of some friction material such, for example, as rubber, leather, etc., is mounted in a forwardly extending bracket 180 and carries a bevel gear 182. This gear meshes with a second bevel gear 184 carried by a shaft 186 which is driven from the main drive shaft 32 by means of a worm 188 and worm wheel 190, Figs. 1 and 2. When a shoe being lasted is held with its side pressed against the roll 20 it will be moved along relatively to the disk 10, finger 12, wiper 14 and nozzle 16 at a uniform speed by means of the frictional engagement of the roll 20. Preferably, the peripheral speed of the roll, and hence the linear rate of movement of the shoe is such that for each pull applied to the stock by an abutment 80 and the cooperating finger 12, the shoe is fed along a distance substantially equal to the width of the effective area of the operating faces 82 and 86. Thus substantially every portion of the lasting margin of the stock will be subjected to the action of the tensioning instrumentalities as the lasting operation proceeds.

Although the various operating elements of the herein illustrated machine may be run at various speeds, it is contemplated that the main drive shaft 32 be driven at a speed of 2400 R. P. M. The speed reduction from this shaft to the disk 10 is 6 to 1 so that the disk will rotate at 400 R. P. M. and, as there are six abutments 80, 2400 seizing and pulling actions will occur each minute. In the illustrated machine, the width of the effective area of the operating faces 82 and 86 of the abutment 80 and finger 12, respectively, is approximately $\frac{1}{16}$ of an inch and the speed of the edge gage roll 20 is such that, for each action of the tensioning instrumentalities, i. e., abutment 80 and finger 12, the shoe will be moved the same distance. The wiper 14 is driven at a speed of

approximately 1200 R. P. M., there being a 2 to 1 speed reduction between the pulleys 152 and 154.

The actions of the separate operating elements of the machine have been fully explained above and it only remains briefly to describe the operation of the machine to last a shoe. In presenting a shoe to the machine when the machine is running, the operator first straightens up a portion of the lasting margin of the stock at the point where the lasting operation is to be initiated and, while holding the shoe with its bottom inclined from the vertical and away from the wiper 14, brings it up until the shoe bottom bears against the right-hand end of the shoe-bottom rest and moves the side of the shoe into engagement with the edge gage roll 20. At the same time he positions the straightened portion of the stock in front of the deflector 134 on the shoe-bottom rest 18. Next, the shoe is swung to place its bottom in a horizontal position and bearing against the shoe bottom rest 18 and the wiper 14. This brings the lasting margin of the stock into the zone of action of the abutments 80 and finger 12 which seize and tension the stock in the manner explained above. The shoe being held in contact with the rotating edge gage roll 20 is moved along at a uniform rate so that successive narrow portions of the lasting margin are presented to the gripping and tensioning action of the abutments 80 and finger 12. As each portion of the lasting margin is thus tensioned and drawn in over the bottom of the shoe, it is immediately acted upon by the rotary wiper 14 which wipes it in and presses it against the shoe bottom. It will be understood that the shoe bottom, adjacent its edge, and/or the inside face of the lasting margin of the stock, will have been previously coated with adhesive so that the action of the wiper will cause the lasting margin to adhere to the shoe bottom. Immediately after the lasting margin has been acted upon by the wiper and secured adhesively to the shoe bottom, a band of adhesive is applied to the exposed surface thereof by means of the nozzle 16. Where the whole shoe is to be lasted, the lasting operation is continued around the entire periphery of the shoe bottom, and when the starting point is approached, and nearly reached, the operator again inclines the shoe to remove the lasting margin from the zone of operation of the abutment 80 and the finger 12. He also lowers the shoe somewhat to bring the narrow portion of the lasting margin not yet acted upon by the abutment 80 and finger 12 underneath the bottom rest. Next, he quickly returns the shoe to its former position in which its bottom is horizontal, and up against the bottom rest, and permits the shoe to be fed along until the aforementioned narrow portion of the lasting margin has been acted upon by the wiper. A similar procedure for finishing off the lasting operation is followed where only a portion of the shoe, e. g., the forepart or shank portion, is being lasted.

Having thus described the invention, what is claimed as new and desired to secure by Letters Patent of the United States is:

1. In a lasting machine, tensioning means comprising a rotary member and means cooperating with said member for seizing successive narrow portions of the lasting margin of stock to be lasted and for drawing each portion inwardly from the edge of, and over, the bottom of a shoe, thereby to tension the stock at different locations along the edge of the shoe bottom as the shoe is moved in a lengthwise direction relatively

to said tensioning means, and wiping means for pressing the lasting margin of the tensioned stock against the shoe bottom in each of said locations.

2. In a lasting machine, tensioning means comprising a rotary member having a plurality of circumferentially disposed abutments and means cooperating with said abutments, in succession, for seizing successive narrow portions of the lasting margin of stock to be lasted and for drawing each portion inwardly from the edge of, and over, the bottom of a shoe, thereby to tension the stock at different locations along the edge of the shoe bottom as the shoe is moved in a lengthwise direction relatively to said tensioning means, and wiping means for pressing the lasting margin of the tensioned stock against the shoe bottom in each of said locations.

3. In a lasting machine, tensioning means comprising a rotary member having a plurality of circumferentially disposed abutments and yieldable means cooperating with said abutments, in succession, for seizing successive narrow portions of the lasting margin of stock to be lasted and for drawing each portion inwardly from the edge of, and over, the bottom of a shoe, thereby to tension the stock at different locations along the edge of the shoe bottom as the shoe is moved in a lengthwise direction relatively to said tensioning means, and wiping means for pressing the lasting margin of the tensioned stock against the shoe bottom in each of said locations.

4. In a lasting machine, tensioning means comprising a rotary disk provided on one face with a circumferential series of axially extending abutments, and a finger cooperating with said abutments, in succession, for seizing successive narrow portions of the lasting margin of stock to be lasted and for drawing each portion inwardly from the edge of, and over, the bottom of a shoe, thereby to tension the stock at different locations along the edge of the shoe bottom as the shoe is moved relatively to said tensioning means, and wiping means for pressing the lasting margin of the tensioned stock against the shoe bottom in each of said locations.

5. In a lasting machine, tensioning means comprising a rotary disk provided with a circumferential series of axially extending abutments and a finger pivoted adjacent to said disk and arranged to cooperate with said abutments, in succession, for seizing successive narrow portions of the lasting margin of stock to be lasted and for drawing each portion inwardly from the edge of, and over, the bottom of a shoe, thereby to tension the stock at different locations along the edge of the shoe bottom as the shoe is moved relatively to said tensioning means, and wiping means for pressing the lasting margin of the tensioned stock against the shoe bottom in each of said locations.

6. In a lasting machine, tensioning means comprising a rotary disk provided with a circumferential series of extending abutments, a finger pivoted adjacent to said disk, and means for moving said finger toward and away from said disk to cause the finger to cooperate with said abutments, in succession, for seizing successive narrow portions of the lasting margin of stock to be lasted, drawing each portion inwardly from the edge of, and over, the bottom of a shoe and then releasing the stock, thereby to tension the stock at different locations along the edge of the shoe bottom as the shoe is moved relatively to said tensioning means, and wiping means for pressing

the lasting margin of the tensioned stock against the shoe bottom in each of said locations.

7. In a lasting machine, tensioning means comprising a rotary disk provided with a circumferential series of axially extending abutments, a finger pivotally mounted adjacent to the disk and having an operating face and means for moving said finger axially with respect to said abutments to cause the operating face of the finger to cooperate with said abutments, in succession, for seizing successive narrow portions of the lasting margin of stock to be lasted, drawing each portion inwardly from the edge of, and over, the bottom of a shoe, thereby to tension the stock at different locations along the edge of the shoe bottom as the shoe is moved relatively to said tensioning means, and wiping means for pressing the lasting margin of the tensioned stock against the shoe bottom in each of said locations.

8. In a lasting machine, tensioning means comprising a rotary disk provided with a circumferential series of axially extending abutments, a yieldable finger pivotally mounted adjacent to the disk and having an operating face, and means for moving said finger axially with respect to said abutments to cause the operating face of the finger to cooperate with said abutments, in succession, for seizing successive narrow portions of the lasting margin of the stock to be lasted, drawing each portion inwardly from the edge of, and over, the bottom of a shoe, thereby to tension the stock at different locations along the edge of the shoe bottom as the shoe is moved relatively to said tensioning means, and wiping means for pressing the lasting margin of the tensioned stock against the shoe bottom in each of said locations.

9. In a lasting machine, tensioning means comprising a plurality of gripping members movable in a circular path and a second gripping member arranged to cooperate with said first-named gripping members, in succession, for seizing successive narrow portions of the lasting margin of the stock to be lasted, drawing each portion inwardly from the edge of, and over, the bottom of a shoe, thereby to tension the stock at different locations along the edge of the shoe bottom, and means for moving said second-named gripping member away from each abutment, in a direction lengthwise of the shoe, for releasing the lasting margin, and wiping means for pressing the lasting margin of the tensioned stock against the shoe bottom in each of said locations.

10. In a lasting machine, tensioning means comprising a gripper jaw movable inwardly over the bottom of a shoe, a second gripper jaw movable relatively to said first-named gripper jaw lengthwise of the shoe into position to cooperate with said first-named gripper jaw to grip the marginal portion of stock to be tensioned, said second jaw being so mounted as to permit it to move inwardly over the shoe bottom with said first-named jaw to pull the stock, and means for imparting to said second-named jaw its movement lengthwise of the shoe into position to cooperate with said first jaw and for thereafter moving said second jaw reversely to release the stock at a predetermined time in the inward movement of the first jaw.

11. In a lasting machine, a rotary lasting device comprising a plurality of spaced gripper jaws movable in succession inwardly over the bottom of a shoe, a gripper jaw movable relatively to said first-named jaws into and out of position to cooperate with each of said jaws to grip the marginal portion of stock to be lasted, said grip-

per jaw being so mounted as to permit it to be moved with each of said first-named gripper jaws inwardly over the shoe bottom to impart to the marginal portion of the stock a pull in a direction inwardly from the edge of the shoe bottom, and means for feeding the shoe continuously past said rotary lasting device to cause said device to act successively on different marginal portions of the stock progressively along the edge of the shoe bottom.

12. In a lasting machine, the combination with work positioning means, of means for gripping the marginal portion of stock to be tensioned, and for pulling it in a direction inwardly from the edge of the bottom of a shoe comprising a pair of gripper jaws relatively movable in directions lengthwise of the shoe and parallel to the edge of the shoe bottom into and out of position to grip the stock, and means for moving said gripper jaws together while in gripping position inwardly over the bottom of the shoe.

13. In a lasting machine, means for tensioning stock to be lasted in different locations along the edge of the bottom of a shoe as the shoe is moved relatively thereto, means for wiping the lasting margin of the stock against the bottom of the shoe in each location, and means for frictionally engaging the side of the shoe operable to effect movement of the shoe relatively to said tensioning and wiping means.

14. In a lasting machine, means for tensioning stock to be lasted in different locations along the edge of the bottom of a shoe as the shoe is moved relatively thereto, means for wiping the lasting margin of the tensioned stock against the bottom of the shoe in each location, and a driven feed roll for engaging the side of the shoe to position it widthwise with respect to said tensioning and wiping means and for effecting movement of the shoe relatively to said tensioning and wiping means.

15. In a lasting machine, means for tensioning stock to be lasted in different locations along the edge of the bottom of a shoe as the shoe is moved relatively thereto, means for wiping the lasting margin of the tensioned stock against the bottom of the shoe in each location, and rotary means for engaging the side of the shoe to position it widthwise with respect to said tensioning and wiping means; said rotary means being operable to effect movement of the shoe relatively to said tensioning and wiping means.

16. In a lasting machine, means for tensioning stock to be lasted in different locations along the edge of the bottom of a shoe as the shoe is moved relatively thereto, means for wiping the lasting margin of the tensioned stock against the bottom of the shoe in each location, and means for engaging the shoe to position it widthwise with respect to said tensioning and wiping means, said last-named means being also operable to effect movement of the shoe relatively to said tensioning and wiping means.

17. In a lasting machine, means for seizing narrow portions of the lasted margin of stock to be lasted and drawing said portions inwardly from the edge of, and over, the bottom of a shoe, wiping means for pressing the lasting margin of the stock against the bottom of the shoe, and means engaging the side of the shoe for continuously moving the shoe relatively to said tensioning and wiping means.

18. In a lasting machine, means for seizing narrow portions of the lasting margin of stock to be lasted and for drawing said portions in-

wardly from the edge of, and over, the bottom of a shoe, thereby to tension the stock at different locations spaced along the edge of the shoe bottom, wiping means for pressing the lasting margin of the stock against the shoe bottom in each of said locations, and means engaging the side of the shoe for effecting relative feeding movement of the shoe and said tensioning and wiping means.

19. In a lasting machine, intermittently operating means for seizing narrow portions of the lasting margin of stock to be lasted and drawing said portions inwardly from the edge of, and over the bottom of the shoe, thereby to tension the stock at different locations along the edge of the bottom of the shoe, wiping means for pressing the lasting margin of the stock against the shoe bottom in each of said locations, and means engaging the side of the shoe for effecting relative feeding movement of the shoe and said tensioning and wiping means.

20. In a lasting machine, means for seizing narrow portions of the lasting margin of stock to be lasted and drawing said portions inwardly from the edge of, and over, the bottom of a shoe, wiping means for pressing the lasting margin of the stock against the bottom of the shoe, and rotary means for engaging the side of the shoe to effect relative movement of the shoe with respect to said tensioning and wiping means.

21. In a lasting machine, means for tensioning stock to be lasted, in different locations along the edge of the bottom of a shoe, means for wiping the lasting margin of the tensioned stock over, and for pressing it against, the bottom of the shoe in each of said locations, and means located adjacent to said wiping means for applying adhesive to the overwiped portion of the lasting margin, immediately after said lasting margin is pressed against the shoe bottom, as the lasting operation proceeds.

22. In a lasting machine, rotary means for tensioning stock to be lasted in different locations along the edge of the bottom of a shoe, means for wiping the lasting margin of the tensioned stock over, and for pressing it against, the bottom of the shoe in each of said locations, and means located adjacent to said wiping means for applying adhesive to the wiped-over portion of the lasting margin, immediately after said lasting margin is pressed against the shoe bottom, as the lasting operation proceeds.

23. In a lasting machine, means for tensioning stock to be lasted in different locations along the edge of the bottom of a shoe, rotary means for wiping the lasting margin of the tensioned stock over, and for pressing it against, the bottom of the shoe in each of said locations, and means located adjacent to said wiping means for applying adhesive to the overwiped portion of the lasting margin, immediately after said lasting margin is pressed against the shoe bottom, as the operation proceeds.

24. In a lasting machine, rotary means for tensioning stock to be lasted, in different locations along the edge of the bottom of a shoe, rotary means for wiping the lasting margin of the tensioned stock over, and for pressing it against, the bottom of the shoe in each of said locations, and means located adjacent to said wiping means for applying a band of adhesive

to the overwiped portion of the lasting margin, immediately after said lasting margin is pressed against the shoe bottom as the lasting operation proceeds.

5 25. In a lasting machine, a shoe-bottom rest having a part extending lengthwise of the shoe bottom, rotary means for seizing successive narrow portions of the lasting margin of stock to be lasted and for drawing each portion inwardly from the edge of the shoe bottom and over said bottom rest part, thereby to tension the stock in a direction heightwise of the shoe at different locations along the edge of the shoe bottom as the shoe is moved relatively to said shoe-bottom rest and said tensioning means, and wiping means adjacent to but spaced from said shoe-bottom rest and tensioning means for pressing the lasting margin of the tensioned stock against the shoe bottom in each of said locations.

10 26. In a lasting machine, a shoe-bottom rest having a part extending lengthwise of the shoe bottom, tensioning means comprising a disk, rotatable in a plane passing through said shoe-bottom rest part, and provided with a circumferential series of abutments, and means cooperating with said abutments, in succession, for seizing successive narrow portions of the lasting margin of stock to be lasted and drawing each portion inwardly from the edge of the shoe bottom and over said shoe-bottom rest part, thereby to tension the stock in a direction heightwise of the shoe at different locations along the edge of the shoe bottom as the shoe is moved relatively to said shoe-bottom rest and said tensioning means, and wiping means adjacent to but spaced from said shoe-bottom rest and tensioning means for pressing the lasting margin of the tensioned stock against the shoe bottom in each of said locations.

15 27. In a lasting machine, a shoe-bottom rest having a part extending lengthwise of the shoe bottom, tensioning means comprising a disk, rotatable in a plane passing through said part and provided with a circumferential series of abutments, and a finger cooperating with each of said abutments, in succession, for seizing successive narrow portions of the lasting margin of stock to be lasted and drawing each portion inwardly from the edge of the shoe bottom and over said shoe-bottom rest part, thereby to tension the stock in a direction heightwise of the shoe at different locations along the edge of the shoe bottom as the shoe is moved relatively to said shoe-bottom rest and tensioning means, and wiping means, adjacent to but spaced from said shoe-bottom rest and tensioning means, for pressing the lasting margin of the tensioned stock against the shoe bottom in each of said locations.

20 60 LLOYD G. MILLER.
